UNITED STATES PATENT OFFICE.

CARLETON ELLIS, OF MONTCLAIR, NEW JERSEY, ASSIGNOR TO SETH B. HUNT,
TRUSTEE, OF MOUNT KISCO, NEW YORK.

PROCESS OF TREATING HYDROCARBON GASES AND PRODUCT THEREOF.

No Drawing.

Application filed February 7, 1922. Serial No. 534,794.

The present application is a continuation in part of my copending application Serial No. 296,052, filed May 10th, 1919, Patent No. 1,412,233, and relates to treatment of hydrocarbon gases containing olefines with sulfuric acid under conditions for producing from the olefines of the gases reactive acid liquor adapted for the replacement of the combined sulfuric acid radical with other groups or radicals to yield alcohols and other products of value.

According to the present invention hydrocarbon gases, that is to say hydrocarbons which are in the gaseous state at ordinary pressures and temperatures, such as natural gas or casing head gas, are cracked to yield substantial proportions of olefines and treated with sulfuric acid to produce such reactive acid liquor.

As has been shown in contemporaneous applications, olefines, such as are present in cracked gasoline or in the gases resulting from the cracking of oils to produce gasoline, may be dissolved in or united with sulfuric acid of a suitable strength, and under certain conditions of temperature to form alkyl sulfuric acids which on hydrolysis by heating with water or treatment with steam give alcohols in a large measure corresponding to the olefines from which the product was derived. For example, the ordinary still gases from a cracking plant may be treated with sulfuric acid of 1.8 specific gravity, and at a temperature preferably around 20° C., to yield an extract that on hydrolysis affords a mixture of isopropyl alcohol and other alcohols including butyl, amyl and the like, but with isopropyl alcohol predominating in amount.

In a similar manner ketones may be obtained advantageously from the secondary alcohols produced as above or by direct oxidation of olefines of a suitable character. The ketones contained, in a general manner, correspond with the alcohol or olefine from which they are derived. Thus from isopropyl alcohol by oxidation with chromic acid or by electrolytic or catalytic oxidation acetone may be obtained; one manner of accomplishing this is to pass isopropyl alcohol admixed with air through a mass of glowing copper or brass gauze whereby the alcohol is largely oxidized to the corresponding ketone, namely acetone. In like manner

methyl ethyl ketone, diethyl ketone and higher ketones may be obtained.

The ethylene which is almost always present in gases of the character described above may be collected in sulfuric acid in the same manner as the higher olefines, but in this case stronger acid and a higher temperature is usually used, although not always necessary. The strength of acid should be adjusted with respect to the temperature to secure a high degree of absorption. As propylene and the higher olefines are polymerized by hot sulfuric acid or acid that is too strong, the absorption of ethylene preferably should take place separately and subsequent to the absorption of all the other olefines. By hydrolysis of the ethylene extract ethyl alcohol is obtained.

The absorption of the olefines in sulfuric acid is facilitated by the presence of a considerable amount of heavy oil and preferably several volumes of heavy petroleum oil are employed to one volume of sulfuric acid. The gases may be bubbled through this mixture under proper conditions of temperature, refrigeration being resorted to when necessary.

With regard to the gases which may be employed, a considerable degree of latitude is possible. The gases useful for the purpose include those derived by cracking heavy asphaltic oils in so-called coking stills, from high pressure stills, such as Burton stills operating on gas oil or fuel oil or other oils, various other types of stills working at atmospheric pressure or below atmospheric pressure, and from tube cracking apparatus into which the heavy oil with or without water or with a small amount of air, is injected and caused to pass through a cracking tube. Other gases, such as various modifications of oil gas, including pintsch gas, blau gas and the like may be used, and the invention claimed herein is concerned more especially with cracked gases, that is to say, the product of cracking operations carried out on hydrocarbons which are in the gaseous state at ordinary pressures and temperatures prior to being subjected to cracking.

The gases used for cracking may be of various kinds. Gases which have been passed under sulphuric acid may be passed through a cracking zone to furnish more un-

saturated material. The heating may be carried out under dehydrogenating conditions to facilitate the yield of olefines. If the cracking is carried out under diminished atmospheric pressure, an improved yield of olefines is obtained, and such procedure constitutes a preferred step of the present invention, but where for other reasons pressure must be employed, it is often desirable to use a catalytic material, such as nickel or copper, in the operation. Dehydrogenation is carried out advantageously with a nickel, copper or brass catalyst. In a similar manner, natural gas or casing head gas and the like may be cracked to produce unsaturated material. Preferably diminished pressure is employed and preferably also a catalyst such as nickel. For example, casing head gas may be passed over nickel at a temperature of between 500 and 700° C., and under a pressure of 7 to 8 pounds below atmospheric to yield a mixture of ethylene, propylene and the like, which may be duly converted into alcohols or ketones and these employed in fuel mixtures or for other uses in the arts.

When casing head gasoline made from natural gas is used as a source of olefines, those fractions boiling between 30 and 55° C., may be used and preferably the lower boiling point from this cut giving a gas or vapor which may consist principally of pentane. In cracking these gases, the rate of flow through the cracking zone should be relatively slow, for instance, in tube cracking, from 8 to 40 cubic feet per hour of gas to each square inch of cross-sectional area of the cracking tube. At a higher rate of flow, a considerable amount of un-cracked material would pass through. At a cracking temperature of 620° C., a yield was obtained in one case of about 18% of olefines higher than ethylene and about 5% ethylene. At a somewhat higher temperature higher olefine yields are obtained. At a cracking temperature of about 720° C., for example, a yield was obtained of about 23.2% of olefines higher than ethylene and about 9.6% of ethylene. The olefines higher than ethylene, which were determined by distillation of the olefine, dibromides to be mainly propylene, are available for absorption in cold sulfuric acid to produce acid extract suitable for hydrolysis to the corresponding alcohols, principally isopropyl alcohol.

The cracked gases obtained as above and containing about 23.2% of such available olefines in admixture with saturated hydrocarbons were passed through a series of four absorbers containing aqueous sulfuric acid of about 1.8 specific gravity, the temperature being maintained under 30° C., or at about 15-20° C. The acid extract obtained, which was practically free from tars and

polymer bodies, was diluted with water and distilled, and upon distillation a large portion of olefines was generated, which may be saved for reabsorption. The yield of alcohol was at the rate of about 1.2 liters per 1000 cubic feet of gaseous mixture treated, but increased yields can, of course, be secured, particularly where provision is made to save the regenerated olefines. The alcohol obtained was of good odor and was about 90% water soluble.

In producing acid extract it is desirable to pass the gases into sulfuric acid until the specific gravity falls from say 1.8 or 1.85 specific gravity to 1.3 or 1.4. Ordinarily the gas is passed in a rapid stream into the mixture of acid or mixture of acid and oil so as to keep the liquid violently agitated but not so violently as to cause heavy foaming and priming. If the container in which the acid is being treated with the gas is about twice the capacity or of such size that the mixture of acid and oil fills it only half or two-thirds, then the gas may be passed through at a rate such as to cause a foam which rises nearly to the top of the container. Ordinarily by such rate of flow of the gas with a gaseous mixture carrying 6 to 10% of unsaturated bodies a period of 8 hours will be required to reduce the specific gravity as indicated. On the other hand, due to the presence of moisture in the gas the specific gravity of the acid may fall through absorption of water and misleading results will be obtained. When hydrogen sulphide is present in the gas it also reacts, tending to weaken the acid and reduce the specific gravity. For these and other reasons the protracted action of the gas on the acid is undesirable and generally speaking 8 to 10 hours is sufficient, giving a good extract and high yield of alcohol, while passage of the same gas for 24 or 48 hours through the acid of like strength might yield a product which on hydrolysis contained little or no alcohol. The treatment of the acid with gas between limiting periods of time as well as limiting ranges of temperatures and with acids of predetermined strength also forms a feature of the present invention.

Further with reference to the absorption of gases containing unsaturated material in sulfuric acid, it should be added that preferably as stated, the gas is passed through acid of the desired strength as, for example, 1.8 specific gravity until the specific gravity has been reduced to 1.3 or 1.4 bearing in mind that the extract may be given a fictitious reduction of gravity by absorption of water from the gas and also that the acid extract is liable to be weakened by polymerization and through other reactions by protracted passage of the gas

therethrough. Hence, it is desirable and in fact important to watch the progress of absorption introducing the gases as rapidly as the sulfuric acid or mixture of sulfuric acid and oil will take up the unsaturated material, but without such an excessive flow of gas that the mixture primes and is carried out of the apparatus by foaming or entrainment to a considerable degree, and in 10 continuing such treatment until the maximum amount of alkyl sulfuric acid is formed. At this point the operation should be stopped and the extract preferably run immediately into water or otherwise diluted in order to effect hydrolyzation. Or if esters such as the acetate, formate and the like are to be prepared, the extract may be treated with the salt of an organic acid.

I claim:

20 1. In the production of alcohols, the steps which consist in passing casing head gas or natural gas through a heated zone under a pressure sub-atmospheric to form olefines and in passing the gases thus produced into 25 sulfuric acid under sulfating conditions whereby an extract is obtained which on hydrolysis yields alcoholic bodies.

2. A fuel prepared by cracking natural gas, absorbing the unsaturated bodies 30 formed in sulfuric acid under sulfating conditions and hydrolyzing the acid material obtained.

3. In the manufacture of acid extract suited for the production of alcohols on 35 hydrolysis, the step which consists in passing cracked gases containing unsaturated components through sulfuric acid under sulfating conditions at such a speed that vigorous agitation takes place without excessive foaming and priming and in stopping the passage of 40 the gas when the content of alkyl sulfuric acid is at a maximum.

4. The process of making reactive acid 45 liquor suited to the production of alcohols on hydrolysis, which comprises cracking gaseous hydrocarbon material and extracting olefines therefrom with sulfuric acid of sufficient strength to form sulfated derivatives of the olefines higher than ethylene at a 50 temperature adjusted to the strength of the acid to avoid undue formation of polymers of such olefines.

5. The process of making reactive acid 55 liquor suited for the production of alcohols on hydrolysis, which comprises cracking natural gas and extracting olefines therefrom with sulfuric acid of sufficient strength to form sulfated derivatives of the olefines higher than ethylene and at a temperature 60 adjusted to the strength of the acid to avoid undue formation of polymers of olefines.

6. The process of making reactive liquor 65 suited for the production of alcohols upon hydrolysis, which comprises cracking natural gas and extracting olefines therefrom with

sulfuric acid until the specific gravity falls from about 1.85 to about 1.4 or 1.3 specific gravity.

7. The process of producing from natural gas reactive acid extract suited for the production of alcohols on hydrolysis, which comprises cracking the gas and treating the cracked gas with sulfuric acid, the effective strength of which is below that of aqueous sulfuric acid of 1.85 specific gravity, and 70 which is of sufficient strength to be adapted for sulfation of the olefines, and continuing such treatment to the production of reactive acid liquor of specific gravity of 1.4 or 1.3. 75

8. The process of making reactive acid 80 liquor suited for the production of alcohols on hydrolysis, which consists in cracking natural gas to produce olefines, extracting the propylene and higher olefines with sulfuric acid of a strength equivalent to that 85 of aqueous sulfuric acid of about 1.8 specific gravity, under temperature conditions to avoid undue polymerization of olefines, and in further extracting the ethylene from such cracked gases separately with higher temperatures and stronger acid, and continuing the extraction to the production of an acid extract of a specific gravity of about 1.3 or 1.4. 90

9. The process of making reactive acid 95 liquor, which consists in cracking natural gas to produce olefines, extracting the olefines higher than ethylene with sulfuric acid of a strength equivalent to that of aqueous sulfuric acid of about 1.8 specific gravity, 100 while maintaining the temperature under about 80° C., and continuing such treatment to the production of reactive acid liquor of about 1.4 to 1.3 specific gravity. 105

10. Reactive acid liquor of specific gravity about 1.3 or 1.4, consisting of the product of extraction treatment, while cooling, of cracked natural gas with sulfuric acid under sulfating conditions, said reactive acid liquor containing principally sulfated derivatives 110 of olefines of cracked natural gas extracted therefrom by the sulfuric acid and present in quantity sufficient to bring the specific gravity from about 1.85 or 1.8 down to about 114—1.3. 115

11. The process of making reactive acid 120 liquor in the production of alcohol bodies, which consists in selecting and cracking low boiling point fractions of casing head gas or natural gas at a temperature of approximately 720° C., to produce olefines, and extracting the propylene and higher olefines under sulfating conditions with sulfuric acid of sufficient strength and under temperature conditions to avoid undue polymerization. 125

12. The process of making reactive acid liquor in the production of isopropyl and other alcohols by hydrolysis, which consists in selecting hydrocarbon components of casing head gas or natural gas boiling from 30° 130

to 55° C., cracking the hydrocarbons to produce olefines, and finally extracting the olefines higher than ethylene with sulfuric acid under sulfating conditions and at a rate to avoid undue polymerization.

13. In the production of alcohols, the steps which consist in passing natural gas hydro-

carbons through a heated zone under a pressure sub-atmospheric to form olefines and in passing the gases thus produced into sulfuric acid under sulfating conditions whereby an extract is obtained which on hydrolysis yields alcoholic bodies.

CARLETON ELLIS.

to 55° C., cracking the hydrocarbons to produce olefines, and finally extracting the olefines higher than ethylene with sulfuric acid under sulfating conditions and at a rate to avoid undue polymerization.

13. In the production of alcohols, the steps which consist in passing natural gas hydro-

carbons through a heated zone under a pressure sub-atmospheric to form olefines and in passing the gases thus produced into sulfuric acid under sulfating conditions whereby an extract is obtained which on hydrolysis yields alcoholic bodies.

CARLETON ELLIS.

Certificate of Correction.

It is hereby certified that in Letters Patent No. 1,594,823, granted August 3, 1926, upon the application of Carleton Ellis, of Montclair, New Jersey, for an improvement in "Processes of Treating Hydrocarbon Gases and Products Thereof," an error appears in the printed specification requiring correction as follows: Page 3, line 62, claim 6, after the word "reactive" insert the word *acid*; and that the said Letters Patent should be read with this correction therein that the same may conform to the record of the case in the Patent Office.

Signed and sealed this 28th day of September, A. D. 1926.
